Term of patent 14 years

(Cl. D14—6)

FIG. 1.

FIG. 2.

FIG. 3.

FIG. 4.

FIG. 5.

FIGURE 1 is a perspective view of the fifth wheel unit embodying my new design;

FIGURE 2 is a top plan view thereof;

FIGURE 3 is a rear elevational view as viewed from the right of FIGURE 1;

FIGURE 4 is a side elevational view as viewed from the side opposite that shown in FIGURE 1; and

FIGURE 5 is a front elevational view as viewed from the left side of FIGURE 1.

The essential features of my design are those portions shown in full lines.

The portions shown in broken lines in FIG. 1 are omitted from FIGS. 2 through 5 for convenience of illustration.

I claim:

The ornamental design for a fifth wheel unit, as shown and described.
